UNITED STATES PATENT OFFICE.

PHILIP DIEHL AND ALFRED GRIEB, OF ELIZABETH, NEW JERSEY, ASSIGNEES TO THE SINGER MANUFACTURING COMPANY, A CORPORATION OF NEW JERSEY.

DESIGN FOR A LOOP-TAKER FOR SEWING-MACHINES.

SPECIFICATION forming part of Design No. 35,525, dated December 31, 1901.

Application filed February 8, 1901. Serial No. 46,586. Term of patent 14 years.

To all whom it may concern:

Be it known that we, PHILIP DIEHL and ALFRED GRIEB, citizens of the United States, residing at Elizabeth, in the county of Union 5 and State of New Jersey, have invented and produced a certain new and original Design for Loop-Takers for Sewing-Machines, of which the following is a specification, reference being had therein to the accompanying drawings, forming part thereof.

The leading or material feature of our design comprises an annulus or ring having an incomplete or notched inwardly-extending flange, on which is formed a loop-taking point 5 or beak, the outer face of which is inclined to intersect the curved inner edge of the said flange at an acute angle.

In the drawings, Figure 1 is a face or plan view of a loop-taker embodying our design; 10 and Fig. 2, a cross-section of the same on line 2 2, Fig. 1.

Referring to the drawings, in which the material features of our design are shown in full lines, *a* denotes a ring or annulus having a

notched or incomplete inwardly-extending 25 flange *b*, on which is formed at one side of the notch or opening in said flange a loop-taking point or beak *c*, the outer face of which is inclined to intersect the inner curved edge of the said flange *b* at an acute angle. 30

The loop-taker is provided with a carrier. (Shown in dotted lines in the drawings.)

We claim—

The design for a loop-taker for sewing-machines, comprising the ring *a* having the incomplete, inwardly-extending flange *b* at one 35 side of the opening in which is the point or beak *c*, the outer face of which is at an acute angle to the inner curved edge of said flange, as shown and described. 40

In testimony whereof we affix our signatures in the presence of two witnesses.

PHILIP DIEHL.
ALFRED GRIEB.
